UNITED STATES PATENT OFFICE

155,898

DESIGN FOR A VENTILATOR

Jay P. Johnson, Euclid, Ohio, assignor to The Swartzwout Company, Cleveland, Ohio, a corporation of Ohio

Application November 4, 1947, Serial No. 142,308

Term of patent 14 years

(Cl. D62—3)

To all whom it may concern:

Be it known that I, Jay P. Johnson, a citizen of the United States, residing at Euclid, in the county of Cuyahoga and State of Ohio, have invented a new, original, and ornamental Design for a Ventilator, of which the following is a specification, reference being had to the accompanying drawing, forming a part thereof.

Figure 1 is a side perspective view of a ventilator, showing my design in open position, and

Figure 2 is an end perspective view thereof in closed position.

I claim:

The ornamental design for a ventilator, substantially as shown.

JAY P. JOHNSON.
